AUTOMATIC SEAL FOR TUBES

Guy T. Griffin, Albany, N. Y.

Application April 17, 1931, Serial No. 530,974

2 Claims. (Cl. 221—60)

For a detailed description of the present form of my invention, reference may be had to the following specification and to the accompanying drawing forming a part thereof, wherein

5 Fig. 1 shows my device in cross section with the valve seated;

Fig. 2 shows my device in cross section with the valve raised;

Fig. 3 shows my device enlarged on a four 10 to one scale;

Figs. 4 and 5 show details.

My invention relates to an automatic valve for collapsible tubes. In particular I apply such a valve to a tube-cap, instead of to the tube 15 itself, as has heretofore been proposed. I also apply the valve so that it will seat downward on top of the cap and provide for its being spring-pressed to its seat. In operation, pressure applied to the contents of the tube, by squeezing 20 its lower end, will cause said contents to exude from the edges of the valve which will be spring-pressed to close when the pressure is released. Referring to the drawing, A represents the top 25 part of a collapsible tube of the well known type adapted to be rolled up from its bottom end as the contents are delivered from its top end. B represents a separable cap adapted to screw on the nipple which projects up from the top of the tube. The cap, as well as the tube, are standard 30 articles at the present time. C represents my valve, which is designed to open outward and seat downward in a hole in the center of cap B. A stem D projects downward from the center of valve C through the central guide opening in 35 a perforated disc E that lies on top of the tube nipple. A spring F surrounding stem D draws downward on the valve, being seated at its upper end against the under side of disc E and at its opposite end seating against a stop on the lower 40 end of the valve stem. The valve C is beveled on its under side and it seats in a corresponding bevel around the edge of the hole in cap B. The angle of that bevel constitutes an important feature of my invention. It should be such that, as the valve 45 goes to its seat, it will expel from that seat any of the plastic contents of the tube which may be trapped in position thereon. I have found that with the opposite edges of the valve standing at an angle of approximately 30 degrees to 50 each other, as shown in the enlarged view of Fig. 3, this result is accomplished. It is also important that the seat on which the valve rests should be narrow, as if it were a cutting edge about ten one-thousandths of an inch. Beyond that distance from the top surface of the valve, the

interior walls of the cap opening may no longer converge but may stand parallel, or even diverge, as appears in Fig. 3 of the drawing. Moreover, by reason of the downward seating of the valve, the natural operation of wiping off the top of 60 the cap will aid the spring in seating the valve. The next important feature is the washer E which serves the function of a guide for the stem D, thus compelling the movement of the valve in a straight line away from or towards the seat in 65 the cap. Otherwise the contents might tend to escape from the valve at one side, instead of equally at all points around its periphery. The washer E is also perforated, as shown in Fig. 5, and the size of the perforations may be adjusted 70 with respect to the consistency of the contents. Thereby the initial outrush of the said contents, when the valve lifts in response to squeezing at the lower end, may be controlled and restrained to the extent desired. The washer E is seated 75 in a circular groove formed between the cap B and the tube-nipple to which the cap is screwed. The spring F, when arranged as shown, may occupy but a small space in the neck of the tube. It should be borne in mind that only a fraction of 80 the upward pressure on the contents caused by squeezing the lower end of the tube, is exerted on the valve to lift it, since the most of that pressure is received by the upper end of the tube itself. Therefore the spring F must yield to 85 allow the valve to lift in response to the aforesaid fraction of the total lifting pressure applied to the contents. Conversely, when the pressure is relaxed the spring F alone must reseat the valve and squeeze out of the valve seat the material left 90 between that seat and the valve. That effect may, however, be supplemented by the aforesaid wiping off. That allows but a weak spring F which may be placed in the neck of the tube without obstructing to any material degree the flow 95 of the contents around it.

By applying my valve to the cap alone and making the cap a vehicle for the valve and its spring, I can make the cap itself a self contained unit, applicable to different packages, and not involving any change or manipulation of the package itself to apply thereto the automatic valve. If desired the cap and valve may be enclosed by a removable film or disc, as shown in Fig. 4, for transportation purposes. It may also be observed 100 that I have avoided by my device all danger from exposure of the contents or any part thereof to the atmosphere, where it may become hardened 105 and interfere with the working of the invention. 110

What I claim as new and desire to secure by Letters Patent is:

1. The combination with a collapsible tube having an outlet extension of a cap having means for removably engaging said extension, said cap having a passageway therein provided with a conical seat, a conical valve constructed and arranged to rest on said valve seat, the surface of said valve seat being beveled on such an angle as to expel material under pressure of the valve thereon, and formed with a cutting edge beyond the bevel, a rod secured to said valve and extended into said tube, an abutment member held in position by said cap and slidably engaging said rod, and a spring extending along said rod

and having one end engaging said abutment member and the other end engaging the rod so as to normally force the valve inwardly against its seat and expel the material between the valve and the seat.

2. A tube seal comprising means providing a passageway having a conical valve seat, a conical valve constructed and arranged to rest upon said valve seat, and means constructed and arranged to normally force the valve inwardly against its seat, the surface of said seat being beveled on such an angle as to provide a cutting edge so arranged that the valve as it seats will expel material between the valve and the seat.
